UNITED STATES PATENT OFFICE.

PAUL S. MILLICE, OF HAMILTON, OHIO, ASSIGNOR TO FIRE-PROOF FURNITURE AND CONSTRUCTION COMPANY, OF NEW YORK, N. Y., A CORPORATION OF NEW YORK.

FILING-CASE.

1,075,369.

Specification of Letters Patent.

Patented Oct. 14, 1913.

Application filed August 17, 1911. Serial No. 644,707.

To all whom it may concern:

Be it known that I, PAUL S. MILLICE, a citizen of the United States, residing at Hamilton, in the county of Butler and State 5 of Ohio, have invented certain new and useful Improvements in Filing-Cases, of which the following is a specification.

My invention relates to metal filing cases, and I have illustrated the same as applied 10 to a card index filing case.

It is the object of my invention to provide a novel construction of metal filing case whereby extreme rigidity is obtained and which is simple in construction and in 15 assembling. In its preferred embodiment I form the body of the case of two pieces which together embrace the top, rear, bottom, front and side walls so connected that the extreme rigidity is obtained.

20 It is further the object of my invention to form the front of the case in novel manner, whereby the connecting bars at the front, which form the spacing members between the openings for the drawers, are formed 25 integral with the body of the case, and further to utilize a portion of the metal displaced in forming said front openings for providing shelf-supporting and drawer stopping means.

30 The invention will be further readily understood from the following description and claims, and from the drawings, in which latter—

Figure 1 represents one of the body members, and Fig. 2 represents the other of the body members, these body members being shown in separated relation. Fig. 3 is a 35 perspective view of my improved device, partly broken away, showing the body members in partly assembled relation. Fig. 4 is a front elevation of the blank, partly 40 broken away, from which the body member shown in Fig. 2 is formed. Fig. 5 is a front elevation of my improved filing case, showing one of the drawers in position and the others of the drawers removed. Fig. 6 is a 45 vertical longitudinal section of the same, partly broken away, taken on the line 6—6 of Fig. 5. Fig. 7 is a cross-section of my 50 improved device, taken on a line corresponding to the line 7—7 of Fig. 6. Fig. 8 is a detail in horizontal section on the line 8—8 of Fig. 6, showing the rear joints between the body members; and Fig. 9 is a detail in 55 cross-section on the line 9—9 of Fig. 5.

11 represents one of the body members, and 12 represents the other of the body members. In the form shown the body member 11 comprises the top 13, the bottom 14, and the rear wall 15 of the filing 60 case, and the body member 12 comprises the side walls 16, 17 and the front wall 18 of the filing case. These respective walls of the filing case, comprised in said respective body members, are integral portions of said 65 respective body members, for purposes hereinafter described.

The top and bottom wall portions of the body member 11, at the side thereof, have their edges bent preferably at right angles 70 to the planes of said top and bottom, respectively for forming flanges 19, 20, which are projected toward each other, and the rear wall portion of said body member 11 has its lateral edges bent forward, prefer- 75 ably substantially at right angles to the plane of said rear wall, for forming flanges 21, which are in line with the respective flanges 19, 20. The top and bottom wall portions of said body member 11 also have 80 their front edges bent at substantial right angles to the planes of said top and bottom for forming flanges 22, 23, which project toward each other.

The front wall portion 18 of the body 85 member 12 has its upper and lower edges reversely bent upon itself, as shown at 26, 27, and the extreme edges thereof, are provided with return bends 28, 29 for forming oppositely opening grooves 30, 31 in which the 90 flanges 22, 23 are respectively received when the case is assembled.

The side wall portions 16, 17 of the body member 12, at their upper and lower edges, are provided with reverse bends 32, 33, the 95 extreme edges whereof are provided with return bends 34, 35, for forming oppositely opening grooves 36, 37, in which the opposed flanges 19, 20 are received when the case is assembled.

The rear ends of the side wall portions 100 of the body member 12 are provided with reverse bends 38, 39, the extreme edges whereof are formed with return bends 40, 41, for forming grooves 42, 43, in which the 105 forwardly extending flanges 21 of the rear wall portion of the body member 11 are received when the case is assembled. By these means an extremely rigid case is provided, constructed of a minimum number of parts, 110

the reverse bends forming one of the walls of the grooves in the body member 11, while the return bends form the other of the walls of said grooves, being closed upon the flanges of the body member 11 for rigidly clamping said flanges in said grooves.

51, 51 represent openings in the front wall portion of the filing case and are adapted to receive the drawers of the filing case, one 10 of which is shown at 52, a suitable number of these openings being provided, depending upon the number of drawers the case is adapted to contain. I form these openings in the integral body member 12, in 15 such manner that separating drawer-ribs shown at 53, 54 are formed between the openings integral with the body member, and thereby provide extreme rigidity and economical construction and avoid the employment of separate pieces, and further 20 avoid the formation of joints or seams in the front of the case, it having been found in practice that filing cases formed with separate bars between the drawer openings secured to the bodies will in shipment or after 25 comparatively slight use show seams or breaks in the finish at the joints between the bars and the bodies irrespective of the methods of fastening employed. In my improved 30 construction I avoid the possibility of the formation of such seams or breaks by forming the parts integral. I prefer to accomplish this by forming the openings substantially as shown in Fig. 4, illustrating 35 a blank, in which the openings are primarily formed as shown at 51^a in such manner as to form lateral wings 55^a, bottom wings 56^a and top wings 57^a, the adjacent wings having diagonal cuts 58 between them. 40 The wings 55^a are bent rearward for forming the lateral flanges 55, the bottom wings 56^a are bent rearwardly for forming the bottom flanges 56, and the top wings are bent rearwardly as shown at 57 and then downwardly as shown at 59, thereby forming 45 rabbets 60 for receiving the upper edges 61 of the drawers 52 for permitting the front of the drawers to be received within the front wall of the case, when the drawer is closed, the drawer also being provided at 50 its rear with an arch-piece 62 arranged to contact the rear-face of the upper flange when the drawer is pulled entirely forward, and thereby preventing accidental removal of the drawer, but permitting intentional removal of the drawer by tilting the drawer upwardly at its front.

65, 65 are shelves. At its forward edge each shelf is provided with a reverse bend 60 66, the extreme edge whereof is provided with a return bend 67 for forming a groove 68 in which the bottom flange 56 of the walls of the drawer opening is received and clamped, the rear of the shelf being shown 65 provided with an up-turned flange 69 suit-

ably secured to the rear wall of the filing case, as by rivets 70. The side edges of the shelves are preferably bent upwardly for forming flanges 71 which serve to strengthen the shelves and provide channels in which 70 the drawers may slide.

The flanges of adjacent drawer openings form separating ribs between said openings which are integral with the body member in which they are formed. They also form 75 crossing U-shaped channels in one of which a channel strip 72 may be received and act as a reinforcing strip, especially at the intersection of said ribs. The channel-strip 80 preferably has lateral flanges 73 whose inner longitudinal ends approach each other, the lateral flanges 55 being formed preferably with their inner ends approaching each other for rigidly inclosing the reinforcing strip between them.

85 My improved construction permits the filing case to be made of comparatively light sheet metal, providing a light case for handling as well as shipping. It forms a case in which all walls are flush with the corners, and provides an extremely rigid case which will not rattle to pieces, and avoids the danger of the opening of joints in shipping and in use of the same.

Having thus fully described my invention 95 what I claim as new, and desire to secure by Letters Patent is:

1. A metal filing case built up of a pair of sheet-metal body-members, each of said body-members having an end and two sides 100 integral with each other, one of said body-members horizontally disposed and the other of said body-members vertically disposed, and locking means between the adjacent edges of said body-members.

105 2. In a metal filing case, a sheet-metal front wall provided with drawer-openings having sheet-metal ribs therebetween, said ribs extending at right angles with relation to each other and being integral with each other and being integral parts of said front wall, said ribs having sheet-metal flanges integral therewith extending rearwardly and forming walls of said openings.

110 3. In a metal filing case, a sheet-metal front wall provided with drawer-openings having sheet-metal ribs therebetween, said ribs extending at right angles to each other and being integral with each other and being integral parts of said front wall, said ribs respectively having separated sheet-metal flanges integral therewith extending rearwardly and forming rearwardly opening channels which cross each other at the adjacent corners of adjacent openings, and a reinforcing strip located in one of said channels and across another of said channels which crosses said last-named one of said channels.

115 4. A sheet-metal front for a filing case 120

- struck up from a blank provided with openings, wings formed at the edges of said openings by diagonal cuts at the corners of said openings, said wings being bent rearwardly for forming walls for said openings whereby sheet-metal ribs are formed between adjacent openings, and said sheet-metal ribs and walls being integral portions of said sheet-metal front.
- 10 5. In a metal filing case, the combination of a body comprising a body-member having a drawer-opening formed therein, the bottom wall whereof is formed by an inwardly extending flange integral with said body-member, and a sheet-metal shelf having a drawer-supporting portion, the lateral edges of said shelf being upturned for forming flanges spaced from said body and which form the sole support of said drawer-supporting portion of said shelf intermediate of the ends of said shelf, said drawer-supporting portion and said upturned lateral edges forming a drawer-receiving channel, the front edge of said shelf provided with 25 a reverse bend terminating in a return-bend forming a groove in which said inwardly extending flange is clamped, and means for securing the rear of said shelf to said case.
6. In a metal filing case, the combination of a pair of body members each comprising three of the walls of said case integral with each other, said body-members arranged at right angles to each other and having therebetween locking joints one of the members whereof is formed by a reverse bend of the edge of a body member and a return bend of the extreme end thereof for forming a groove and the other member of which joint is formed by a flange formed up from the other body member and received in said groove wherein it is locked for locking said two members together.
- 30 In testimony whereof, I have signed my name hereto, in the presence of two subscribing witnesses.
- 35 PAUL S. MILLICE.
